UNITED STATES PATENT OFFICE.

JOHN C. STUTZ, OF ALBUQUERQUE, NEW MEXICO.

DOOR AND SASH STICKING MACHINE.

Application filed February 4, 1925. Serial No. 6,773.

This invention relates to new and useful improvements in wood working machines, and particularly to sash and door stickers.

It is well known that in cutting the sticking of door and window sashes, the various members of a door or sash are sometimes warped or bowed longitudinally, and that the sticking machine will cut the sticking along the curved edges to the required depth, with the result that the door or sash member is still bowed, and cannot be used. In correcting this error in the door or sash member, the ordinary woodworker runs the member through a planer or jointer, to cut the edges of the member straight and in parallel relation to each other, after which the member is run through the sticker.

It is the principal object of the present invention to provide a machine wherein the door or sash member, which is bowed, is straightened up and cut with the required sticking, at the same operation.

In stickers now in use, the door or sash member is run through the machine on its edge, thus requiring that the operator prepare the member for this operation, by running it through a planer or jointer.

Another object of the present invention is to provide a machine wherein the door or sash member is run through the machine on its wider flat face, thereby permitting a cutting action on the edge faces of the member, to straighten the member, as well as to produce the sticking thereon.

Another object is to provide a machine of this character wherein cutters and guides are arranged to be moved toward and away from each other for action upon the opposite edge faces of a door or sash member, to produce parallel side edges, and at the same time to produce the sticking on said edges.

Briefly, the invention comprises a stationary frame or bed, on which is mounted a transversely slideable, and adjustable member or bed. On the stationary base there is mounted a feeding means and a cutter, while a similar feeding means, and a similar cutter are mounted on the movable bed, suitable guiding means being carried by the beds, whereby upon transverse movement of the movable bed, the cutter thereof will be brought toward and away from the cutter of the stationary bed, with the result that sash and door members, of different widths, may be readily accommodated, and the edge

faces thereof trimmed into parallel relation, and provided with the desired sticking.

Other objects and advantages will be apparent from the following description when taken in connection with the accompanying drawings.

In the drawings:

Figure 1 is a side elevation of a sticking machine made in accordance with the present invention.

Figure 2 is a top plan view of the same.

Figure 3 is an end view, looking toward the feed table.

Figure 4 is an end view, looking from the opposite end of the machine.

Figure 5 is a vertical transverse sectional view on the line 5—5 of Figure 1.

Figure 6 is an enlarged elevation of the member 62, which extends transversely of the center of the machine.

Figure 7 is a diagrammatic view showing the action of the cutters on a bent or curved piece of work.

Figure 8 is a vertical transverse sectional view on the line 8—8 of Figure 1.

Referring particularly to the accompanying drawings, 10 represents the stationary portion or bed of the frame of the machine, which has, at one end, the cut out portion 11. The vertical wall of the cut out portion 11 is formed with a rib 12, which extends transversely of the frame, while the bottom wall has a parallel pair of similar ribs 13. The upper portion of the elevated end of the stationary frame or bed 10, at one side thereof, is cut out transversely of said portion, as shown at 14 and 15, to receive rotatably therein, the sprocket wheels 16 and 17, of the feed chain 18, which chain is supported thereby. The shaft 19, of the sprocket wheel 16 extends transversely of the machine, and to a suitable distance beyond the remote side thereof, where it is supported by the bracket arm 20, mounted on the side of the bed portion 10. On this end of the shaft 19, outwardly of the bracket arm 20, are mounted the sprocket wheels 21 and 22. The shaft 23, of the sprocket wheel 17 also extends transversely of the machine, and has its other end supported in the adjustable bracket 24, mounted on the side of the bed 10. Secured to the said side of the bed 10, adjacent the point of attachment of the arm 20, is a horizontal outwardly extending arm 25, and mounted on the outer end of this

arm is the motor 26, the shaft of which carries the sprocket wheel 27. A drive chain is engaged around the sprocket wheel 27 and the sprocket wheel 22, of the shaft 19, whereby said shaft is driven. Secured on opposite sides of the portion 10, and bent to extend partially across the ends of the cut out 11, are the bracket arms 28 and 29, which rotatably support the opposite ends of the longitudinally grooved shaft 30. One end of the shaft 30 is provided with a sprocket wheel 31, and engaged around this sprocket, and the sprocket 21, of the shaft 19, is a drive chain 32. Splined on the shaft 30 is a collar 33, and keyed on this collar is a sprocket wheel 34, retaining collars 34 being removably secured on the ends of the collar 33, at the opposite sides of the sprocket 34.

Slidably transversely in the cut out 11, is the movable and adjustable bed 35, which is formed with the grooves 36, to receive the ribs of the bed 10. The end of the bed 10, outwardly of the outer side of the bed 35, is extended upwardly and inwardly, as shown at 37, and disposed within this portion, and having a rib 38, received in a groove 39, formed in the adjacent face of the movable bed 35, is a block 40. Adjusting screws 41 are engaged through the portion 37, and bear against the said block, whereby to move the same into frictional engagement with the bed 35. Clamping or locking screws 42 are engaged downwardly through the inwardly extending part of the said portion 37, to engage with, and hold, the block against movement, and thereby retain the bed 35 in adjusted position. Supported on this portion 37 is the feed table 43, the top of which is in the approximate plane of the upper end of the movable bed 35.

Formed longitudinally through the movable bed 35, in a direction transversely of the machine, is a threaded opening 44, and threaded through this opening is the adjusting screw shaft 45, the said shaft being rotatably supported, at one end, in a bracket 46, mounted on the bed 10, adjacent one end of the cut out 11. The upper portion of the bed 35 is cut out at 47, similarly to the portions 14 and 15, to receive the sprocket wheel 34, and a similar sprocket wheel 48, said sprocket wheels having the feed chain 49 engaged therearound. The shaft 50, of the sprocket wheel 48 is mounted in the adjustable bracket 51, carried by the movable bed 35.

Mounted on an adjustable bracket, which as shown, is mounted on the side of the bed 10, adjacent the feed chain 18, at 52, is a motor 53, the shaft 54 of which extends vertically and carries a cutter 55 on its upper end, in position to operate upon the adjacent edge of a sash or door member fed through the machine. A second motor 56 is mounted on a similar bracket 57, on the end of the

movable bed 35, and has its shaft 58 extending vertically and provided with a cutter 59, for operation upon the other edge face of the sash or door member.

Mounted on the bed 10, adjacent the motor bracket, is an upwardly extending arm 60, the upper end of the said arm extending inwardly to overlie the feed chain 18, said end being provided with a longitudinal series of transversely extending hold down rollers 61, which engage on the upper face of the work. It will be noted that there is a space between the sprockets 17 and 34, and disposed within this space, and supported by the vertically adjustable bracket 62, is a transverse roller 63, said roller extending transversely of the machine. Supported on the upper end of the arm 60 are the arms 64, and rotatably supported in these arms 64 is a roller 65, said roller cooperating with the roller 63 to hold the work, while passing from the feed chain 49, to the feed chain 18.

Mounted on the end of the movable bed 35, adjacent the motor 56, is a vertical arm 66, the upper end of which extends inwardly over the feed chain 49, and is provided with the rollers 67, similar to the rollers 61, for engagement on the upper face of the work, in cooperation with the chain 49, which engages with the lower face of the work.

On the end of the screw shaft 45, adjacent the bracket 46, is a hand wheel 68, for rotating the shaft to move the bed 35 transversely of the machine, and thereby adjust the cutter 59 toward and away from the cutter 55.

On one end of the roller 63 there is mounted a sprocket wheel 69, and associated with the sprocket wheel 17 is a sprocket wheel 70, a chain 71 being engaged around these sprockets to transmit motion from the sprocket 17 to the roller 63.

Each of the hold down rollers 61 and 67 is urged against the work by the coil springs 72, and are of a length approximately equal to the width of the feed chain.

In the diagrammatic view, Figure 7, there is shown a door member 73, in position for action by the cutters, said member being warped or bowed longitudinally. It is the idea to cut or trim this piece of material so as to utilize the greater portion thereof. The material will be trimmed along lines 74, so that the side faces will be parallel. It will be noted that the lines 74 are tangent to the concave and convex side faces of the material so that there will be the minimum of waste. The operator then moves the bed 35 transversely to position the cutter 59 in proper relation to the cutter 55, so that the shallowest portion of each cutter will cut into the door member along one of the

lines 74, to the proper depth to form the sticking.

Mounted in advance of the cutter 59 is a chip breaker 75, while a similar chip breaker 76 is mounted adjacent and in advance of the cutter 55. The breaker 76 is, however, connected with the advanced end of the rear guiding fence 77, which is adjustably mounted on the table 43, at one end, and on the upper portion of the bed 10, at its other end. A second guiding fence 78 is mounted on the bed 10, beyond the cutter 55, and is arranged to engage with the edge of the sticking cut by the cutter 55. It will be noted that the fence 77 is set outwardly of the line of the fence 78, such distance being equal to the distance between the portion of the edge of the door member which engages with this fence, and the nearest line 74 thereto. At the other side of the bed 10, at the same elevation as that of the fence 78, is a guiding fence 79, against which the edge of the door member engages, after having been cut by the cutter 59.

It will be seen that, as the advanced end of the door member passes from the feed chain 49 to the feed chain 18, there would be a tendency to sag down, on the part of said end of the member, but by reason of the member 62, and the roller 63, this is effectively prevented, and the member properly and evenly guided or carried over to the chain 18.

If sticking is to be made on both of the edges of the member 73, the cutter 59 is replaced by one of the desired outline.

While I have described the present invention as particularly applicable to sticking, I wish it understood that the machine is readily adapted for glue jointing such members as table tops, or any built up members desired. The particular feature of the present machine being that both edge faces of a piece of work may be treated in such manner as to provide for perfectly fitting joints, whereas in devices heretofore one edge was treated, thus requiring the reversal of the work to treat the other face. The machine

is also capable of forming sticking on one 50 or both edges of a door or sash member.

What is claimed is:

1. A machine of the class described comprising a stationary member having an elevated portion at one end and a depressed portion at the other end, transverse rails on the said depressed end portion, a second base member slidably mounted on the said rails, a cutter on the elevated portion, a cutter on the second base member, a work guide on the said elevated portion extending into proximity to the second cutter, means for simultaneously driving the cutters, and work guiding means between the base members driven by the cutter driving means and arranged in parallel relation to said rails. 55

2. A machine of the class described comprising a stationary member having an elevated end and a depressed end, a cutter on the said elevated end, a member transversely 70 adjustable on the said depressed end, a cutter on the adjustable member, a work guide mounted on the said depressed end and extending transversely of the adjustable member and into proximity to the first cutter, 75 and a work guide mounted on said elevated end and extending into proximity to the second cutter and in parallel relation to the first work guide.

3. A machine of the class described comprising a stationary member, a member adjustable transversely on the stationary member, a cutter on the stationary member, a cutter on the adjustable member, a work guide associated with the first cutter and 80 extending transversely of the path of the adjustable member, a work guiding means associated with the second cutter and extending across the stationary member, and adjustable with said cutter, superimposed 85 rollers disposed transversely on the stationary member adjacent the adjustable member between which the work is guided, and means for simultaneously driving the cutters and one of said guiding rollers. 90 95

In testimony whereof, I affix my signature.

JOHN C. STUTZ.
